LIGHTING FIXTURE

Leroy C. Doane, Meriden, Conn., assignor to The
Miller Company, Meriden, Conn., a corporation
of Connecticut

Application May 12, 1932, Serial No. 610,801

1 Claim. (Cl. 240—78)

The present invention relates to lighting fixtures and is more particularly directed toward an indirect lighting fixture.

The present invention contemplates an indirect lighting fixture having an annular shade, preferably made of opaque material such as metal, and having a diffusing member in the center of the shade underneath the light source.

According to the present invention, this diffusing member is arranged to be removably supported by the shade and is made of glass of comparatively low optical density and, in order to avoid the appearance of bright spot on account of this glass being close to the light source, the diffusing member is provided with an annular depending skirt which shields the inner portions of the diffuser against observation at angles near the horizontal. This skirt may be supplemented by an additional annular ring-like member inside the skirt. In order to ornament the fixture this glass member may be provided with grooves, facets, and the like, which break up the light rays.

Other and further objects will appear as the description proceeds.

The accompanying drawing shows, for purposes of illustrating the present invention, one of the many embodiments in which the invention may take form, it being understood that the drawing is illustrative of the invention rather than limiting the same. In the drawing:

Fig. 1 is a sectional view with parts in elevation showing an indirect lighting fixture; and

Fig. 2 is an inverted plan view of the same.

The fixture shown in the drawing is one designed more particularly for securing to a pendant lamp socket already installed. The support for the fixture is in the form of a socket extension 10 adapted to be threaded into the lamp socket and adapted to receive a lamp bulb 11. The socket extension 10 is provided with the usual external insulating band or covering 12. The insulating band 12 is surrounded by a supporting band 13, preferably in the form of a tubular sheet metal element having a downwardly bent inner portion 14 which fits the insulating band very tightly. The tubular member 13 is forced on to the socket from underneath and the parts fit so tightly that the metal shell cannot be removed. The lower end of the shell is provided with three outwardly bent portions 15 adapted to receive the upper ends 16 of three wire supports 17. These ends are welded or soldered to the ring 13. They are made of resilient material such as steel or hard brass wire and are bent outwardly at the lower ends, as indicated at 18.

An annular dished shade 19 is supported from members 17. This shade carries three sheet metal clips 20 having openings to receive the ends 18 of the wire members. The shade 19 may have any suitable ornamental shape and is designed to upwardly reflect light. The shade has an annular flange 21 at the lower edge adjacent the lamp bulb 11.

The central opening in the shade 19 is closed by a glass diffuser 22 preferably made of glass of low optical density, such as crystal glass acid dipped, and of such size as to rest on the flange 21 of the shade 19. It is placed close to the lamp bulb and, in order to avoid the bright spot which would result from using a plain piece of diffusing glass, the disk 22 is, as shown in the drawing, provided with a depending skirt 23 and a depending annular ring-like portion 24. These parts are comparatively deep and prevent direct observation of the body of the disk at angles near the horizontal without substantially interfering with the transmission of light downwardly.

The surface brilliancy of the side walls of the depending skirt and ring-like portion is considerably less than the surface brilliancy of the thin part of the disk 22 and hence the fixture presents a more pleasing appearance with less glare. In order to break up the light rays and further ornament the glass, the same is provided with ribs or facets such as indicated at 25. The disk 22 is held in place in any convenient manner, for example, by bending downwardly the lower ends 26 of the clips 20.

When it is desired to relamp the fixture the wire members 17 are bent inwardly to release the shade and the shade and glass diffuser may be lowered to give access to the lamp bulb.

It is obvious that the invention may be embodied in many forms and constructions, and I wish it to be understood that the particular form shown is but one of the many forms. Various modifications and changes being possible, I do not otherwise limit myself in any way with respect thereto.

What is claimed is:

A semi-indirect lighting fixture comprising a pendant lamp bulb, an upwardly and outwardly flaring reflector below the lamp bulb and having a central aperture underneath the bulb, a diffusing glass disk having an upper flange resting on the surface of the reflector adjacent the aperture and a diffusing annular skirt projecting below the reflector, and a second annular depending ring-like portion inside the skirt.
